UNITED STATES PATENT OFFICE.

CHARLES E. SHADALL, OF MILWAUKEE, WISCONSIN, ASSIGNOR TO SHADALL MANUFACTURING COMPANY, OF WAUWATOSA, WISCONSIN, A CORPORATION OF WISCONSIN.

FLUSHING AND VENTILATING APPARATUS.

1,242,251.

Specification of Letters Patent.

Patented Oct. 9, 1917.

Application filed January 10, 1917. Serial No. 141,503.

To all whom it may concern:

Be it known that I, CHARLES E. SHADALL, a citizen of the United States, residing at Milwaukee, in the county of Milwaukee and 5 State of Wisconsin, have invented certain new and useful Improvements in Flushing and Ventilating Apparatus, of which the following is a specification, reference being had to the accompanying drawing, forming

10 a part thereof.

This invention relates to apparatus for flushing and ventilating water closets, urinals and the like.

The main objects of the invention are to 15 combine in a single fixture, flushing and ventilating apparatus; to facilitate installation and operation of the apparatus; and generally to simplify and improve the construction and operation of devices of this 20 class.

It consists in the construction, arrangement and combination of parts as herein-after particularly described and pointed out in the claims.

25 In the accompanying drawing like characters designate the same parts in the several figures.

Figure 1 is a vertical section of combined flushing and ventilating apparatus embodying the invention as applied to a water closet bowl; Fig. 2 is a view partly in side elevation and partly in vertical section, showing a modification of the apparatus; and Fig. 3 is a cross section on the line 3—3, Fig. 1.

35 Referring to Figs. 1 and 3, the apparatus comprises a casing 1, provided with a removable cover 2, and containing a flush valve chamber 3 and an aspirator chamber 4. The chamber 3 is provided with a normally closed flush valve 5, which controls the supply of flushing water to a closet bowl 6, or other fixture with which the apparatus is connected. This valve, which may be constructed and operate in various ways, is in 40 the present case, as shown, provided with a stem 7, freely fitting in a socket or guide 8, depending from the cover 2, and is adapted when released, to be closed and held closed by the water pressure against a seat 9, which is preferably removable and renewable. Within the valve chamber below the valve seat 9 and in alinement therewith, a cylinder or expansion chamber 10 is formed, and this chamber is provided with a piston

or movable part 11, which is connected with the valve 5 and adapted to open the same and retard its closing. The expansion chamber is connected by a water supply passage or port 12, with the upper or inlet part of the valve chamber 3, and this port or passage is controlled by a normally closed valve 13, which is provided with a stem 14 passing upwardly through a stuffing box 15 on the cover 2. A spring 16, co-operates with the water pressure to close the valve and hold it upon its seat. A restricted discharge passage or port 17, provided with an adjustable regulating valve 18, threaded in the case 1 and accessible from the outside, leads from the expansion chamber 10 into a discharge chamber or passage 19, with which the valve chamber 3 below the valve seat communicates outside of said expansion chamber through an annular or segmental passage or opening 20, as shown in Fig. 3.

The aspirator chamber 4 is formed with a mixing tube or air entraining conduit 21, communicating at the upper end with a foul air inlet passage 22, leading upwardly from a chamber or enlargement in the lower part 80 of the case. The lower part of the chamber 4 has a water sealed discharge port or opening 23, into the passage 22.

Above and in axial alinement with the tube or passage 21, a water inlet and jet opening 24 is formed in a wall below and parallel with the cover 2, and on this wall is formed a chamber 25 having an inlet port above and in axial alinement with the opening 24. The inlet port to the chamber 25 is normally closed by a valve 26, having a stem 27 extending upwardly parallel with the valve stem 14 through a stuffing box 28 on the cover 2. A spring 29, interposed between said valve and the cover, assists the water pressure to close and hold said valve upon its seat. A self-centering spreader 30, pivotally connected with the valve 26, is adapted when shifted upwardly with the opening of said valve, to reduce the area of the jet opening 24 and produce a symmetrical cone-shaped spray or jet of water, which is most effective for entraining air with it through the tube or conduit 21. The spreader also serves to dislodge any dirt or foreign matter which may be caught or collect in the jet opening, and to keep said opening clear.

A lever 31, which may be operated by any suitable means, such as a handle 32, is pivotally connected with the valve stems 14 and 27, and is adapted when turned downward, to open the aspirator valve 26, and when turned upward to open the flush controlling valve 13, the stem of either valve serving as a fulcrum support for the lever in opening the other valve.

The body of the case 1 is formed or provided with pipe connections for a water supply pipe 33, which leads into the flush valve chamber 3 above the valve 5, a foul air discharge pipe 34, which leads out of the aspirator chamber 4 into which the tube or conduit 21 opens at its lower end above the water sealed discharge port or opening 23, and two pipe fittings or couplings 35 and 36, which connect the discharge chamber 19 and the lower end of the passage 22, with separate passages 37 and 38, which communicate with the upper part of the closet bowl 6, the passage 37 leading into the flush rim 39 of the bowl. The passages 22 and 38 and the pipe fitting or coupling 36, serve both to conduct foul air from the bowl into the aspirator chamber, and to discharge the water used to operate the aspirator into the bowl.

In the operation of the apparatus as thus far described, when the bowl 6 or other fixture is in use, the lever handle 32 is depressed, thereby opening the valve 26, while the valve 13 remains closed. Water is thus admitted through the port 26, chamber 25 and opening 24, into the upper part of the aspirator chamber 4, the spreader 30 being drawn upwardly into the opening 24 and forming therewith a conical jet or spray of water in the tube or conduit 21. Foul air is thus drawn from the bowl 6 or other fixture through the passage 38, pipe fitting 36 and passage 22, and entrained with the jet or spray through said tube or conduit into the lower part of the chamber 4, as indicated by arrows in Fig. 1. In the lower part of the chamber 4 the air separates from the water and is discharged through the pipe connection 34, while the water is discharged through water sealed port 23 into the lower part of the passage 22, and flows thence through the pipe fitting 36 and passage 38 into the bowl. The bowl or other fixture is thus effectively ventilated while it is in use. Afterward, the lever handle 32 is momentarily lifted, thereby closing the valve 26 and opening the valve 13. Water is admitted from the supply connection 33 through the passage 12 into the chamber 10 below the piston 11, the piston is forced upwardly and the valve 5 lifted from its seat. Water then rushes from the upper part of the chamber 3 through the port uncovered by the valve, into the lower part of said chamber, thence through the passage 20, chamber 19, pipe

fitting 35 and passage 37, into the flush rim 39, from which it is discharged in a spray or film and flushes the bowl.

Water escaping from the chamber 10 through the restricted passage 17 when the valve 13 is closed, allows the piston 11 to descend and the valve 5 to close gradually according to the adjustment of the regulating valve 18, by which the duration of the flushing operation is determined.

The operation of the modified form of the apparatus shown in Fig. 2 is substantially the same, except that water from both the chambers 3 and 4 is discharged into the bowl or other fixture, and air is drawn therefrom through a single connection 35'. This form of the apparatus is applicable to a bowl or other fixture of the ordinary construction having a flushing connection such as 37, as shown in Fig. 1, but when the discharge from the opening or openings from the flush rim or other connection is quite restricted, a bowl or other fixture of special design, having a separate passage or connection 38 for the discharge of water from the aspirator and the withdrawal of foul air from the bowl or other fixture, is desirable, as shown in Fig. 1. With a bowl or fixture of such construction, the passage 22 is separated from the discharge passage or chamber of the flush valve by a partition 40, as shown in Fig. 1.

Various changes in the details of construction and arrangement of parts may be made without materially affecting the operation of the apparatus and without departure from the principle and scope of the invention as defined in the following claims.

I claim:

1. In flushing and ventilating apparatus the combination of a casing containing separate flush-valve and aspirator chambers and provided with water supply and discharge connections and a foul air discharge connection, a flush-valve controlling the flow of water through the flush valve chamber, a valve controlling the admission of water to the aspirator chamber, and means for opening either of said valves.

2. In flushing and ventilating apparatus the combination of a casing containing separate flush-valve and aspirator chambers and provided with water supply and discharge connections and a foul air discharge connection, self-closing valves controlling the passage of water through the flush-valve chamber and aspirator chamber respectively, and a lever for opening either of said valves.

3. In flushing and ventilating apparatus the combination of a casing containing separate flush-valve and aspirator chambers and provided with water supply and discharge connections and with a foul air discharge connection, self-closing flush and aspirator valves, an expansion chamber having a mov-

able part connected with the flush valve and provided with a water supply passage and a restricted discharge passage, a flush-controlling valve normally closing said supply

5 passage, and means for opening either the aspirator valve or the flush-controlling valve.

4. In flushing and ventilating apparatus the combination of a casing containing flush-

10 valve and aspirator chambers and provided with water supply and discharge connections, an air entraining conduit in the aspirator chamber having a foul air inlet connection and a water inlet at one end and

15 communicating with the foul air discharge connection at the other end, flush and aspirator valves controlling the flow of water through said chambers and conduit, a water sealed outlet from the aspirator chamber

20 below the foul air discharge connection, and means for opening either of said valves.

5. In flushing and ventilating apparatus the combination of a casing containing flush valve and aspirator chambers and provided

25 with water supply and discharge connections and a foul air discharge connection, an air entraining conduit in the aspirator chamber, a port opening from the inlet side of

30 the flush-valve chamber into the aspirator chamber adjacent to one end of said conduit, a water discharge and foul air inlet passage opening into the same end of said conduit which communicates at the other end

35 with the foul air discharge connection, a water sealed discharge opening from the aspirator chamber into said air inlet passage below the foul air discharge connection, valves

40 controlling the passage of water through said chambers, and means for opening either of said valves.

6. In flushing and ventilating apparatus the combination of a casing containing flush valve and aspirator chambers and provided

45 with water supply and discharge connections, self-closing valves controlling the passage of water through said chambers and having stems passing outwardly through the

case, and a lever connected with the valve

stems and adapted when moved in one direction to open one valve and when moved in 50 the opposite direction to open the other valve.

7. In flushing and ventilating apparatus the combination of a casing containing flush-valve and aspirator chambers and provided

55 with water supply and discharge connections and a foul air discharge connection, an air entraining conduit in the aspirator chamber communicating at one end with

60 said foul air discharge connection, water and foul air inlet ports opening into the aspirator chamber at the other end of said conduit, a water sealed discharge opening from the aspirator chamber below the foul air discharge connection, flush and aspirator valves

65 controlling the passage of water through said chambers, an expansion chamber having a movable part connected with the flush valve, a water inlet port and a restricted

70 discharge port, self-closing valves normally closing the water inlet ports of the expansion and aspirator chambers and having

75 stems projecting through said casing, and a lever connected with said stems and adapted to open either of said valves while the other remains closed.

8. In flushing and ventilating apparatus the combination of a casing containing separate flush-valve and aspirator chambers and provided with a water supply connection for

80 the flush-valve chamber, a foul air discharge connection for the aspirator chamber and a water discharge connection for each chamber, the water discharge connection for the

85 aspirator chamber serving also as a foul air inlet, a port opening from the inlet side of the flush-valve chamber into the aspirator chamber, a valve controlling the passage of

90 water through the flush valve chamber, a valve controlling the admission of water to the aspirator chamber through said port, and means for operating said valves.

In witness whereof I hereunto affix my signature.

CHARLES E. SHADALL.
